UNITED STATES PATENT OFFICE.

ALFRED J. KULL, OF NEW HAVEN, CONNECTICUT.

MEAT-CHOPPING MACHINE.

SPECIFICATION forming part of Letters Patent No. 519,000, dated May 1, 1894.

Application filed May 19, 1893. Serial No. 474,747. (No model.)

To all whom it may concern:

Be it known that I, ALFRED J. KULL, a citizen of the United States, and a resident of New Haven, in the county of New Haven and State of Connecticut, have invented certain new and useful Improvements in Meat-Chopping Machines, of which the following is a specification.

My invention relates to improvements in meat-chopping machines, and more particularly to that class in which vertically reciprocating knives or teeth are used, and is especially designed to simplify and cheapen this class of machines and to produce one which shall be easily operated and constructed.

To this end my invention consists in an upper and lower series of cutting knives, the former mounted in a vertically reciprocating holder, and the latter in a rotating table suitably mounted and constructed for operation.

Upon the accompanying drawings, illustrating my invention, similar figures and letters of reference denote like parts throughout the several views.

Figure 1, is a side elevation of my improved machine and in which the upper series of cutting teeth are shown in a raised position. Fig. 2, is a front elevation showing the rotatable table and the base for the same in section upon a line as indicated by $x-x$ in Fig. 1. Fig. 3, is a detail plan of the table, partly broken away.

In the accompanying drawings 1 is a base, and 2 a main support for the rotating table.

A. Said table is provided with beveled teeth 3 upon its under side which mesh with a beveled driving pinion 4 upon a short shaft 5, one end of said shaft being journaled in the before-mentioned base, and the other in a suitable bracket 6. I also mount upon said

shaft a suitable bifurcated arm 7 having a handle upon its outer extremity, and also provide it with a pawl 8 adapted to engage a ratchet wheel 9 which is keyed to shaft 5. This arm 7 is connected by means of a link

10 with a lever 11, one end of which is hinged to the base of the machine. The other end is designed to be engaged by a vertical rod

12 which is properly secured to the upper reciprocating holder B. Upon the under side

of lever 11 I place a spring 13 for the purpose of operating the pawl and ratchet in con-

junction with the holder B, and their connections, as will later be more fully explained.

14 is a standard in which is mounted a vertically disposed rod 15, the lower end serving 55 to receive and support the holder B, and the upper end carrying a suitable operating handle 16. Around said rod and above the standard I place a spiral spring 17 for the purpose of returning the holder and rod at all times 60 to a raised position. I also provide an adjusting washer upon said rod for this spring.

In order to readily get at both the upper and lower cutting knives 18 I make the upper holder detachable by means of a thumb-screw 19 which appears in Figs. 1 and 2. In the rotating table A I preferably arrange the cutting teeth in circles, as shown, and between each I place suitable circular releasing or freeing strips 19^a. These strips are loosely 70 fitted between the circles of cutting teeth and rest upon small spiral springs 20 by means of which they are subjected to a slight vibration during the operation of the machine, the purpose being to release the meat from the 75 teeth at proper intervals during the operation. For the purpose of retaining the meat upon the table I place a casing 21, which is supported upon uprights 22, the lower ends of which are made fast to the base 2. It will 80 be readily seen by the drawings that the construction of the machine is such that both the rotating table and the holder B can be easily removed for cleaning or repairs.

A description of the operation of the machine would be practically as follows: After placing the meat to be chopped in the machine, the operator would simply force the holder down against the action of a spring 17 by the manipulation of the handle 16, the connections, as seen in Fig. 1, of rod 12, lever 11 and the pawl and ratchet upon shaft 5, and the table would be caused to rotate, making the operation complete. The teeth are all made separate and independent of each other and 95 can be set and replaced independent of each other.

Having thus described my invention, what I claim, and desire to secure by Letters Patent, is—

1. In a machine of the class described, a base having mounted upon it a rotating table

provided with cutting teeth, and upon its under side having beveled gear teeth adapted to mesh with suitable driving mechanism, and an upper reciprocating holder carrying teeth 5 and suitably mounted above said table, and designed to operate in conjunction with the same, for the purpose described and set forth.

2. The combination in a meat-chopping machine, of a base, a table mounted upon said 10 base and adapted to rotate, a shaft suitably journaled and carrying a beveled pinion whereby said table is driven, a pawl and ratchet upon said shaft, and means as shown whereby the same is operated, as shown and 15 described.

3. In a machine for chopping meat, the com-

bination with a rotating table, of a series of reciprocating cutters mounted in a rotating holder, a vertically disposed spring-actuated rod, a standard in which the same is mounted, 20 connections as shown between the holder and the rotating table, and a handle upon the rod whereby the whole is operated, substantially as shown and described.

Signed at Bridgeport, in the county of Fair- 25 field and State of Connecticut, this 6th day of May, A. D. 1893.

ALFRED J. KULL.
